UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed January 27, 1919, Serial No. 273,235. Renewed August 14, 1924.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to typewriting machines, and is herein disclosed as applied to an Underwood typewriting machine of the so-called fan-fold billing type, wherein the usual revoluble platen is adapted to be swung clear of the feed rolls against which it normally holds fan-fold or other webs or sheets, to enable the readjustment of carbon sheets between said sheets or fan-fold webs through the manipulation of a carbon-paper carriage. Such machines are now on the market, and 20 are well adapted to produce identical copies of writing, by means of the carbon sheets, upon forms printed upon the webs, provided the forms do not exceed eleven inches or thereabouts in length.

25 It has been found that if the carbon-paper carriage is given a travel of more than about eleven inches, it becomes somewhat awkward to manipulate, because the handle by which the typist manipulates the carbon-paper carriage comes only about as far forward as the front of the typewriter carriage, so that pushing the carbon-paper carriage very far rearwardly requires an undue extension of the arm of the typist when seated 30 at the typewriting machine, and an awkward reaching forward by bending the body over the typewriter keyboard. A form, requiring a greater travel of the carbon-paper carriage, also entails the use of a gaging arm 35 extending above the platen in excess of the length of the usual arm, with the result that the gaging arm vibrates unpleasantly, making the operation of the machine noisy, this vibration being due to the fact that the arm 40 is necessarily light to avoid overloading the typewriter carriage, while the weight of the gage makes its end heavy.

Moreover, if the gaging arm is more than eleven or twelve inches in length, as measured from the center of the platen, the end of the arm is normally out of reach of the typist without rising in her seat. Besides this, the use of some forms of gage, such as aligning pins, on the gaging arm may be 55 attended with some danger, since the typist

usually swings the platen upwardly by drawing forwardly and downwardly on the gaging arm until it is horizontal. While the arm is horizontal, the typist usually pushes the carbon-paper carriage rearwardly, with 60 the result that, in a rapid sequence of these operations, a long gage arm comes unpleasantly near the face, especially near the eyes and hair, and, in fact, a gage for a fourteen inch form would actually strike the head of 65 the typist. This is partly due to the fact that if the form, viz, the severed sheet, is longer than the travel of the carbon-paper carriage, the backward travel of the carbon-paper carriage will fail to carry the carbon 70 sheets clear of the usual knife. This necessitates the turning of the platen backward, preparatory to severing the sheets after the web is gaged. To allow for this, an extra length of web must be gaged, equal to the 75 amount the platen is to be turned back. Thus, if the form is three inches longer than the travel of the carbon-paper carriage, the length of web to be gaged will be six inches 80 longer than that travel.

I have found it possible to overcome all these difficulties, by utilizing, for the writing of longer forms, the present carbon-paper carriage with the usual rails on which it has the usual travel of about eleven inches. To 85 do this, without materially cutting down the efficiency of the machine, I have found it advantageous to utilize a telescoping or extensible gaging arm which may be of substantially as light build as the arm now in use, 90 and which, nevertheless, may be extended to a length sufficient to gage forms of fourteen inches or more in length. This gaging arm advantageously includes a paper-puller, and for this purpose may be provided with pins 95 on which the typist may impale the web or webs while swinging the platen upwardly, in the usual manner. The typist can then extend the gaging arm to its full length 100 while pinching the web to the paper-puller until the web is straightened out. The typist then grips the straightened-out web as it lies upon the usual front paper table by pressure of the finger upon it. This enables 105 the typist to hold the web at a convenient point while manipulating the carbon-paper carriage by means of a handle, said handle being like the usual handle except that it is advantageously longer. The typist holds 110 the webs in this manner until the platen is

swung back to writing position, when the gage arm may collapse automatically by its own weight.

According to the present invention, a front stop is provided for the carbon-paper carriage, which, at the end of its backward movement, abuts against a rear stop, as usual. The above-noted paper-puller, provided with web-impaling pins, constitutes a web-holding device for grasping the web to draw it forward past the platen to the desired extent. As the web is drawn forward by means of said device, at first the carbon-paper carriage, by reason of friction between the carbon-sheets and the web, moves forward until it is arrested by its front stop, after which the web is drawn further forward, thus producing initially the over-shift or excess movement of the web relatively to the carbon-sheets. The above-mentioned telescoping or extensible gaging arm may comprise a guide-arm and a slide-bar, which latter, at its outer end, adjustably carries said device for grasping the web to draw it forward. The guide-arm at its outer end is provided with a stationary stop which may be formed by a guide-loop, and with which a similar stop-forming guide-loop carried by the inner end of the slide-bar to move therewith may co-operate to limit the forward movement of the web-holding device, thereby to enable the automatic measuring of sections of web of a length greater than that provided for by the travel of the carbon-paper carriage between its stops. The length of the web-section measured is determined by the distance between the front stop for the carbon-paper carriage and the web-holding device when the latter is arrested in its forward movement by means of the stationary stop provided on the guide-arm. While the web is manually held at its most forward position, the carbon-paper carriage is moved rearwardly against its rear stop, thereby to produce finally the normal extent of shift of the carbons relatively to the work-web, and re-position the carbons relatively to the web for typing the next set of forms or web-sections. Because of the fact that the measured length of forms or web-sections to be written upon are of greater length than the extent of travel of the carbon-paper carriage, the correspondingly longer carbon-sheets will project at the front of the platen after the carbon-paper carriage has been retracted against its rear stop. Accordingly, after the platen has been returned to the writing position, it is rotated backwardly for thereby positioning the first unwritten section of web, together with the interleaved carbon-sheets, relatively to the writing line on the platen, and also to bring the typed sheets into position to be severed by the usual knife. The present invention, therefore, may be considered as comprising means for

measuring off sections of web of a length greater than the machine otherwise would be capable of using.

Other features and advantages will hereinafter appear.

In the accompanying drawings,

Figure 1 is a perspective view, largely diagrammatic, and with many parts omitted, of an Underwood typewriting machine of the fan-fold type, showing the present invention as applied thereto.

Figure 2 is a sectional side view of the same when beginning to gage the web.

Figure 3 is a view showing the relationship of the parts just thrown up preparatory to extending the gaging arm for the purpose of gaging the web.

Figure 4 is a view similar to Figure 3, but showing the web gaged with the gaging arm extended.

Figure 5 is a view similar to Figure 4, with the carbon paper carriage pushed rearwardly to readjust the carbon sheets relatively to the web.

Figure 6 is a view similar to Figure 5, but showing the parts after the platen has been thrown back to normal position and the extended gaging arm has collapsed.

Figure 7 is a view similar to Figure 6, showing the parts after the carbon sheets and the webs have been retracted by backward turning of the platen and the forms just filled in have been detached.

In the usual Underwood fan-fold typewriting machine, a fan-fold web 10, or a series of webs, is drawn forward over a rear bar 11 of a framework 12, forming an extension of the typewriter carriage 13, and passes downward over a rod 14 and over a paper table 15. Then it passes the rear feed roll 16 and the front feed roll 17, which carry it around and hold it against the platen 18, so that the web may lie on a front paper table 19, extending above the platen.

In order to rotate the platen to advance the web, the usual line-space handle 20 may be actuated to drive rearwardly the usual slide 21, which is effective by means of the usual pawl, not shown, to rotate the line-space wheel 22 fast to the axle 23, on which is also fast a pinion 24 and the universal knob or handle 25. As is usual in the fan-fold machines, the pinion 24 drives the platen, because the platen 18 is fast to a second pinion 26, identical with the pinion 24, both pinions meshing with the idle pinion 26a fast upon a shaft 27.

When the web 10 is drawn forward, it draws forward along with it the carbon sheets 28, which are attached in the usual manner by means of clips 29 to a carbon-paper carriage 30, so that characters written by the types 31 upon the outer sheet of the web 10 will be reproduced by the

carbon paper upon the inner sheets of the web. When a form is thus written upon and filled out line after line, and advanced by the line-space lever 20, it extends upward above the front paper table 19 and lies upon a gage arm 32 in full sight of the typist.

According to the present invention, when a form is completely filled out, it will often extend its leading end 33 beyond the end of the gage arm 32, as shown in Figure 1 and also in full lines in Figure 2. When the form is thus filled out and lies in this position, the typist presses rearwardly a catch 34, which normally engages a lug 35 upon a handle 36, thereby releasing said handle and permitting the typist to draw forward upon the handle 36, and thereby rotate the usual swing frame 37, in which the platen is journaled. As the swing frame 37 rotates around the shaft 27, the gage arm 32 swings forward to the Figure 3 position, because it is fast to the front paper table 19. Before swinging the platen in the manner described, the typist usually finds it most convenient to gage the web 10 by causing openings 38 therein to fit upon one or more pins 39, which serve as one form of end gage or paper-puller, said pins being fast upon a plate 40, which is slidably mounted on the gage arm 32. Where a plurality of superposed separate webs are used, impaling the webs on the pins serves to realign them if any have crept relatively to the others. This gaging causes a temporary bending of the web and the carbon sheets, as shown in dotted lines at 41, Figure 2, but this bending is immaterial, since the typist draws the plate 40 out along the gage arm 32, on which it is slidably mounted, until the pins 39 reach the limit of their travel, shown in Figure 4. The pins 39 and plate 40 form a web-holding device for grasping the web 10 to draw it forward past the platen. This drawing forward of the web 10 draws forward the carbon-paper carriage 30, because of the friction of the carbon sheets 28 upon the various plies of the web 10. The carbon-paper carriage, however, can only come partway forward, because it strikes a fixed front stop 42, as shown in Figure 4, with the result that the drawing of the web 10, after the carbon carriage 30 strikes the stop, causes the web to move forwardly relatively to the carbon sheets.

In order to permit the sliding of the plate 40 relatively to the gage arm 32, the plate 40 is adjustably mounted by means of a thumb screw 43 upon the outer end part of a slide-bar 44, said slide-bar sliding in a bracket or slide 45, forming a guide-loop having bent-over ends 45^a embracing the bar 44 and fast to the free end of the gage arm 32, which forms a guide-arm. In order to

guide the lower end of the slide-bar or arm 44, it carries a bracket 46, which forms a slide, or guide-loop, having bent-over ends 46^a, embracing the guide-arm 32 and slideable thereon, with the result that the plate 70 40 must always slide parallel to itself, since the slide-bar 44 is guided by the two slides or guide-loops 45 and 46.

To preserve the accurate alignment of the gage or pins 39 relatively to the axis of the gage arm 32, the plate 40 is provided with a U-shaped extension 47, similar to the usual gage of the fan-fold machine, and having the thumb screw 43 passing through the bottom of the U, and bearing against the back of the slide-bar 44. The limit of the throw of the web-holding or web-grasping pins 39 is determined by the striking of the bracket or guide-loop 46, forming a movable stop, against the bracket or guide-loop 45 which forms a stationary stop, and the point at which the pins will be thus arrested may be varied by adjusting their position upon the slide-bar 44. The stop 45, for limiting the outward movement of the web-holding device, comprising the impaling pins 39 and the slideable plate 40, co-operates with the front carbon-paper carriage stop 42 to enable the automatic measuring of sections of web of a length greater than that provided for by the limits of travel of the carbon-paper carriage 30.

When the carbon sheets are in the Figure 4 position, the typist may shift the carbon sheets rearwardly along the web by pushing rearwardly upon the handle 48, which, being fast to the carbon-paper carriage 30, has been brought above the front of the keyboard. This slides the carbon carriage rearwardly along its usual rails 49, which form the sides of the framework 12. In the structure herein disclosed, the handle 48 is longer than the usual one by about five inches, thus bringing the handle to a point near the front of the keyboard, where it is convenient, even if the typist bends rearwardly out of the way of the end of the gage slide 44 when thrown forward. The carbon-paper carriage 30 is arrested at the rearward limit of its travel by an adjustable rear stop or pin 50, thus arresting the carbon paper at the point seen in Figure 5. The carbon sheets 28 are now correctly positioned relatively to the next succeeding unwritten set of forms or web-sections, although both the carbon sheets and new forms project for some distance at the front of the platen 18, by reason of their extra length. At this time, or earlier, the typist usually seizes the web 10 by pressing it against the front paper table 19 with the thumb adjacent one of the usual side gages 51, inasmuch as it is more convenient to handle the web at this point than adjacent the extended plate 40.

120
125
130

Since the typist can easily hold a web in place by pressure of the thumb upon the paper table 19, the web may be allowed to drop clear of the pins 39. At this time, if desired, the typist then swings the platen back to normal position, with the result that the slide arm 44 will automatically slide back, under the influence of gravity, to the Figure 6 position, in which the U 47 lies 5 against the slide 45, or else the bracket 46 lies against a stop 53, the web usually falling over the rear end of the slide arm 44, as shown in Figure 6. This slightly advances the carbon-paper carriage 30, be- 10 cause the stretch of web between the front paper table 19 and the rear paper table 15 is lengthened by being bent around the platen, instead of being extended straight, as seen in Figure 5. The typist then ro- 15 tates the platen rearwardly by the usual handle knob 25 to the Figure 7 position, to bring the ends of the carbon sheets just above the writing line and just below the usual knife 54. The typist then severs the 20 typewritten forms by drawing them against the knife 54 or operating the knife in any usual or desired manner, with the result that the typewritten forms are severed at the proper point and the new forms stand 25 ready to be written on at the printing point.

In order to permit the proper positioning of the carbon sheets relatively to the printing point, when moved rearwardly to the Figure 5 position, the rear stop 50 may be 30 adjustably positioned in any one of the usual openings 55. It will be observed that the gage arm 32 need be no longer than the usual arm, so that there is little more ten- 35 dency for it to rattle or to vibrate than in the usual machine. By using the above-de- 40 scribed web-holding device together with the limitedly extensible arm shown, it is possible to employ forms (and carbon sheets of corresponding length) having a 45 length, when severed, considerably longer than the travel of the carbon-paper car- riage.

The fact that the web and carbon sheets 50 together bend up to form the bend 56, seen in Figure 7, is immaterial, since the feed rolls 16 and 17, by holding the web against the platen, hold the carbon sheets with it at the same time.

It will be observed that this invention 55 enables existing machines to be changed over for the writing of longer forms, since the usual arm, corresponding to the arm 32, may be readily detached by loosening the thumb screw 57, which holds it in place. 60 This enables it to be lifted off the dowel pin 58, which steadies it. The usual handle may be easily replaced by the handle 48, since it is held in place by nuts 59 screwed down on bolts 60, which pass through the 65 body of the carbon-paper carriage, and

through openings in the base 61 of the handle. Not even the skill of a repair man is needed to place these new parts on the machine, and which co-operate with the features thereof to enable the typing of 70 work on forms of considerably greater length than could otherwise be used.

It will be observed that the extra length of web to be measured from the knife by the 75 slideable web-holding device is about double the length of the form on the web in ex- 80 cess of the travel of the carbon-carriage, but this does not interfere with easy and accurate measuring, owing to the fact that this device, when the arm 32 is horizontal, 85 is convenient to the typist's hands.

Variations may be resorted to within the scope of the invention, and portions of the improvements may be used without others.

Having thus described my invention, I 85 claim:

1. In a typewriting machine, in combina- 90 tion, a platen-frame, a platen revoluble therein, and work-sheet-positioning means comprising a sheet-holding device for grasp- 95 ing the forward end of a work-sheet to draw it past the platen, and a support, on the outer end of which said sheet-holding de- 100 vice is mounted, said support being col- 105 lapsible, whereby the forward end of said work-sheet may be grasped by said sheet- 110 holding device, when said support is col- 115 lapsed, and the work-sheet drawn for- 120 ward until the support is restored to its full length; means being provided for me- 125 chanically limiting the extending move- 130 ment of said support.

2. In a typewriting machine, in combina- 105 tion, a platen-frame, a platen revoluble therein, and work-sheet-positioning means comprising a device whereby the forward 110 end of a work-sheet may be held to draw it past the platen, and a support, on the outer end of which said sheet-holding de- 115 vice is mounted, said support being col- 120 lapsible, whereby the forward end of said work-sheet may be held by said sheet-holding device, when said support is collapsed, 125 and the work-sheet drawn forward until the support is restored to its full length, the collapsible support comprising at its outer end a guide along which said holding de- 130 vice is slidable, means for mechanically limiting the extending movement of said support, and means for securing said holding device in any desired position.

3. In a typewriting machine, in combina- 125 tion, a traveling typewriter carriage, a platen revoluble in said carriage, a carbon- sheet-carriage slidable on the typewriter carriage, means to limit the forward and rearward movement of said carbon-sheet- carriage, and means capable of gaging web sections of greater length than provided for by the forward travel of the carbon-car- 130

riage, and in connection with the use of carbon-sheets of a length corresponding to that of said sections, said means comprising a gaging member on which the forward end 5 of the web may be held and drawn forward therewith, and a support for said gaging member to enable said sections of greater length to be gaged, said support being collapsible and normally in collapsed condition, and opened out by the movement of 10 said gaging member, means being provided for mechanically limiting the opening movement of said support.

4. In a typewriting machine, in combination, a traveling typewriter carriage, a platen revoluble therein, a sheet-holding device for grasping a work-sheet to draw it forward past the platen, a slide-bar upon which said device is mounted, a guide-arm 20 for the slide-bar mounted on the typewriter carriage at the delivery side of the platen and upon which said device carried by the slide-bar is slidable outward with the slide-bar beyond the free end of the guide-arm, 25 a stop for limiting the outward movement of the slide-bar on the guide-arm to enable the automatic measuring of a portion of said work-sheet drawn forward by said device, and means for adjusting said device 30 along the slide-bar for variably determining the length of the portion of the work-sheet measured by said device.

5. In a typewriting machine, in combination, a traveling typewriter carriage, a platen revoluble therein, means for raising the platen to permit a web to be straightened out and drawn forward thereunder, a web-holding device for grasping the web to draw it forward past the platen, a slide-bar 40 upon which said device is mounted, a guide-arm for the slide-bar mounted on the typewriter carriage at the delivery side of the platen and upon which said device carried by the slide-bar is slidable outward with the 45 slide-bar beyond the free end of the guide-arm, and a stop for limiting the outward movement of the slide-bar on the guide-arm to enable the automatic measuring of sections of said web by said device when the 50 slide-bar is drawn out against its said stop.

6. In a typewriting machine, in combination, a traveling typewriter carriage, a platen revoluble therein, a front paper-table on said carriage, a guide-arm adapted to be 55 detachably mounted on the front paper-table, a sheet-holding device for grasping a work-sheet to draw it forward past the platen, a slide-bar carrying said device and slidable along the guide-arm to move said 60 device outwardly beyond the free end of the guide-arm, and a stop for limiting the outward movement of the slide-bar on the guide-arm to enable the automatic measuring of a portion of said work-sheet drawn 65 forward by said device.

7. In a typewriting machine, in combination, a traveling typewriter carriage, a platen revoluble therein, a front paper-table on said carriage, a guide-arm adapted to be detachably mounted on the front paper-table, a sheet-holding device for grasping a work-sheet to draw it forward past the platen, a slide-bar carrying said device and slidable along the guide-arm to move said device outwardly beyond the free end of 70 the guide-arm to an extent substantially equal to the length of the guide-arm, a guide-loop carried by the inner end of the slide-bar and embracing the guide-arm, another guide-loop on the outer end of the 80 guide-arm and embracing the slide-bar, said guide-loops acting as co-operating stops for limiting the outward movement of the slide-bar on the guide-arm to enable the automatic measuring of a portion of said work-sheet 85 drawn forward by said device, and means for adjusting said device along the slide-bar for variably determining the length of the portion of the work-sheet measured by said device. 90

8. In a typewriting machine, in combination, a traveling carriage, a platen revoluble therein, a swing-frame for raising the platen to permit a web to be straightened out and drawn forward thereunder, 95 a web-holding device for grasping the web to draw it forward past the platen, a slide-bar upon which said device is mounted, a guide-arm for the slide-bar mounted upon the swing-frame at the delivery side of the platen to swing forward therewith, and guiding connections between the slide-bar and the guide-arm providing for the movement of said device outwardly beyond the free end of the guide-arm, said connections 100 including a stop for limiting the outward movement of the slide-bar on the guide-arm to enable the automatic measuring of sections of said web by said device when the slide-bar is drawn out against said stop. 110

9. In a typewriting machine, in combination, a traveling carriage, a platen revoluble therein, a swing-frame for raising the platen to permit a web to be straightened out and drawn forward thereunder, a web-holding device for grasping the web to draw it forward past the platen, a slide-bar upon which said device is mounted, a guide-arm for the slide-bar mounted upon the swing-frame at the delivery side of the platen to swing forward therewith, and guiding connections between the slide-bar and the guide-arm providing for the movement of said device outwardly beyond the free end of the guide-arm, said connections including a 115 stop for limiting the outward movement of the slide-bar on the guide-arm to enable the automatic measuring of sections of said web by said device when the slide-bar is drawn out against said stop, said guiding connec- 120

125

130

tions providing free sliding movement permitting said device to return automatically to normal position on the guide-arm when the guide-arm is swung rearwardly by the 5 swing-frame to restore the platen to the typing position.

10. In a front-strike typewriting machine, the combination with a platen and a frame upon which the platen is mounted 10 for upward displacement from typing position to permit straightening out of a work-web thereon, of a carrier for carbon-sheets, said carrier movable forwardly with the work-web and backwardly relatively 15 thereto, means to limit the forward movements of the carbon-carrier, means to limit the rearward movements of the carbon-carrier, whereby relative shifting may be effected between the work-web and the carbons to an extent limited by the range of 20 movement of the carbon-carrier, the displaced condition of the platen permitting also an additional relative shifting of work-web and carbons by drawing forward the 25 work-web while the carbon-carrier is detained by its front stop, an overshift gage mounted at the delivery side of the platen for displacement with the platen-frame to position to gage the extent of the overshift, 30 whereby the machine is adapted to handle a work-web printed with a succession of forms each of which has a length in excess of the range of travel of said carbon-carrier, and a web-severer upon the platen-frame in position to sever the web in 35 position for the first line of typing upon the fresh form thereon, said severer so placed that, when the platen is restored to typing 40 position, the carbons project past the severer, the platen being rotatable backwardly to clear the carbons from the severer and bring the web to severing position.

11. In a front-strike typewriting machine, the combination with a platen and a 45 frame upon which the platen is mounted for displacement from typing position upwardly to permit straightening out of a work-web thereon, of a carrier for carbon-sheets, said carrier movable forwardly with the

work-web and shiftable rearwardly relatively thereto, and a gage for the leading end of the straightened-out work-web, said gage mounted at the delivery side of the platen to be displaced together with said platen-frame, and comprising members 55 loosely linked together, one of said members fixed upon said platen-frame and the other having means whereby its movement of extension is mechanically limited, said members being constantly loose for relative 60 opening and collapsing movements.

12. In a front-strike typewriting machine, the combination with a platen and a frame upon which the platen is mounted for upward displacement from typing position to permit straightening out of a work-web thereon, of a carrier for carbon-sheets, said carrier movable forwardly with the work-web and backwardly relatively thereto, means to limit the forward movements of the carbon-carrier, means to limit the rearward movements of the carbon-carrier, whereby relative shifting may be effected between the work-web and the carbons to an extent limited by the range of movement 75 of the carbon-carrier, the displaced condition of the platen permitting also an additional relative shifting of work-web and carbons by drawing forward the work-web while the carbon-carrier is detained by its front stop, and an overshift gage mounted 80 at the delivery side of the platen for displacement with the platen-frame to position to gage the extent of the overshift, whereby the machine is adapted to handle a work-web printed with a succession of forms each of which has a length in excess of the range of travel of said carbon-carrier, said gage comprising members loosely linked together, one of said members fixed upon said platen-frame and the other having means whereby 85 its movement of extension is mechanically limited.
